UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,164,359.

Specification of Letters Patent. Patented Dec. 14, 1915.

Application filed January 7, 1915. Serial No. 933.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States, No. 436,532, to O. Mergenthaler, wherein circulating matrices are released from a magazine in the order in which their characters are to appear in print and then assembled in line, the composed line transferred to the face of a mold, the mold filled with molten metal 20 to form a slug or linotype against the matrices which produce the type characters thereon, and the matrices thereafter elevated and returned through a distributing mechanism to the magazine from which they 25 started. More particularly, it relates to machines of this class equipped with a plurality of magazines which are movably arranged in such manner that any selected one thereof may be brought into operative relation to the other parts; and its object primarily is to provide means whereby any one of such magazines may be removed from the machine without disturbing the other or others.

35 In the accompanying drawings, I have shown my invention embodied in the specific class of machine known as the "Model K", or as illustrated in my Letters Patent No. 1,104,512, but it is equally applicable to machines of other kinds, or to type-setting and type-casting machines, etc., which handle type or dies instead of matrices. In other words, I have shown my invention only in preferred form and by way of example, and 40 obviously many changes and variations may be made therein, and in its mode of application, which will still be comprised within its spirit. Generally speaking, I desire it to be understood that I do not limit myself to 45 any specific form or embodiment, except in so far as such limitations are specified in the claims.

50 Referring to the drawings: Figure 1 is a side view, partly in section, of a portion of

a linotype machine having my invention applied thereto; Fig. 2 is a similar view showing the parts in different position; Fig. 3 is a section on the line 3—3 of Fig. 2; Fig. 4 is a view taken from the opposite side of the machine; Fig. 5 is a similar view showing the lowermost magazine in process of removal; and Fig. 6 is a section on the line 6—6 of Fig. 4.

The matrices are stored according to font in the magazines A and B, which may be 55 shifted so as to bring either into operative relation to the face plate C in the manner well understood in the art. In the form illustrated, only two such magazines are disclosed, but obviously the number thereof 60 may be increased if desired, as the principles of adjustment and operation apply similarly to a greater number. The magazines A and B are respectively equipped with series of 65 banks of escapements *a* and *b*, and as each 70 magazine is selected and moved into position, its escapements are thereby brought 75 into operative relation to a single series or bank of escapement actuating levers C¹ (Fig. 1) which are operated by the reeds C² from 80 a keyboard mechanism, all in the usual manner. The magazines A and B are mounted upon the customary base frames A¹ and B¹, which in turn are carried by the supporting 85 frame E, and with reference to which they 90 are shifted to bring the selected magazine into operative position. The supporting frame E rests upon and is sustained by the framework of the machine, it being pivotally 95 movable about a rod E¹ upon which it 100 rests near its upper end.

As previously stated, the magazines A and B and their frames A¹ and B¹ may be shifted relatively to the supporting frame E so as to bring one or the other into operative position. The lower base frame B¹ is provided at opposite sides and near the upper end thereof with guiding pieces F which are slidably engaged with the supporting frame E, and near its lower end with further guiding pieces F² which bear against anti-friction rollers on the frame E, the guiding pieces thus serving to hold the parts in accurate relationship during their movements. The magazine B rests upon the base frame 105 B¹ in the usual manner, and the upper base frame A¹ in turn lies upon the magazine B, it being pivotally connected near its upper

end and at opposite sides thereof to upward extensions of the guides F as by the open slots F¹. The magazine A similarly rests upon and is carried by the base frame A¹.

5 The vertical shifting of the magazines with reference to the supporting frame E is effected by means carried by said frame which will now be described. Near the forward end of the frame and at opposite sides thereof are located two elevating cams G mounted upon a transverse rock shaft G¹ suitably journaled in the frame. These cams engage rollers B²⁰ (Figs. 1 and 2) connected at opposite sides to the base frame B¹ and are rotated by means of a handle J connected to the shaft G¹. At the rear or upper portion of the supporting frame E and at opposite sides thereof are provided two pairs of toggle links H and H¹, the upper members H being connected at one end to the base frame B¹ and the lower members H¹ at one end to the supporting frame E. The respective upper and lower members H and H¹ are intermediately connected to a common transverse rod H², the lateral movement of which acts to straighten out the compound toggle system. The rod H² is connected by a pair of longitudinal links H³ to the cams G at the front of the frame, so that when the shaft G¹ is turned, the cams G and toggles H, H¹ will act to elevate the magazines simultaneously and in proper parallel relation.

35 The parts so far described, except as hereinafter specified, are or may be of the same construction as shown in my Letters Patent previously mentioned, and are herein designated by substantially the same letters of reference.

40 As previously stated, my invention contemplates the provision of means whereby the individual magazines may be removed conveniently and independently. The removal of the upper magazine A may be effected just as in my previous Letters Patent, the only requirement being that it be shifted above the level of the face plate C, in which position it may be lifted off its base frame A¹ and drawn forwardly, as shown by dotted lines in Fig. 1. The removal of the lower magazine B, however, is more difficult, as it will be noted that the extent of movement of the magazines, as controlled by the cams G and the connected mechanism, is not sufficient to locate it above the level of the face plate. I have therefore provided means distinct from the shifting mechanism, whereby the magazines in their entirety may be elevated and sustained, so that access may be freely had to the lowermost magazine. In order to secure this result, I preferably employ a handle K mounted on a short shaft K¹, suitably journaled in the machine frame, and having an arm K² which is pivotally con-

nected to a link K³ depending from the shaft G¹ in the supporting frame E. The depression of the handle K therefore effects the rocking of the frame E and all the connected parts about the supporting rod E¹, 70 raising its lower end to such extent as to locate the lowermost magazine B above the level of the face plate C. In order to hold the frame in its elevated position, I so proportion the parts that the handle K in its active throw will "pass center" and bring up against a stop K⁴ depending from the framework. 75

With the parts in this position, the magazine B is free to be removed, and in order to facilitate it, I provide further means for separating from it the overlying magazine A and its connected base frame A¹, which latter normally rests upon the magazine B. These means (Figs. 4, 5 and 6) comprise a handle L pivotally mounted upon a stud L¹ projecting laterally from the base frame A¹, and pivotally connected as at L² to an upwardly arm L³ mounted to rock upon a stud L⁴ projecting from the base frame B¹. 90 It will be seen that by turning the handle L forwardly about its stud L¹, the base frame A¹ will be rocked about its pivot F¹, and carried away from the underlying magazine B, thus giving ample space for the latter to be lifted off its base frame B¹ and withdrawn forwardly from the machine, all as shown by full lines in Fig. 5. In order to sustain the base frame A¹ and its magazine A in raised position, I so proportion the parts that the throw of the handle L will cause it to pass center and bring its nose L⁵ up against a shoulder L⁶ projecting laterally from the arm L³. The magazines during removal may be supported by a pair 95 of arms M, which may be connected to either 100 of the base frames in the customary manner.

In the present instance, when the magazine B is to be removed, it is raised to its highest position with relation to the frame E before the latter is rocked upward by the handle K. It will be understood, however, that the extent of movement of the frame E by the handle K may be varied, if desired, to shift the magazine into position 110 for removal without regard to its relative location in the frame. These and other modifications will readily suggest themselves to those skilled in the art without departure 115 from the scope of my invention. 120

In some instances it may be desirable to separate the magazines for some other purpose than to remove the lowermost one as above described, and it will be understood that my invention is not to be limited to 125 this or any other specific adaptation except in so far as such limitations are specified in the claims.

Having thus described my invention, its construction and mode of operation, what I 130

claim and desire to secure by Letters Patent of the United States, is as follows:

1. In a typographical machine, the combination of a plurality of magazines facing in the same direction, and a supporting frame therefor movably mounted in the machine frame, said magazines being shiftable relatively to the supporting frame to bring one or another thereof into operative position, 10 with means for moving the supporting frame from its normal position to facilitate the removal of the magazines.

2. In a typographical machine, the combination of a plurality of magazines facing in the same direction, and a supporting frame therefor movably mounted in the machine frame, means carried by the supporting frame for shifting the magazines relatively thereto to bring one or another into operative position, with means for moving the supporting frame from its normal position 20 to facilitate the removal of the magazines.

3. In a typographical machine, the combination of a plurality of magazines facing in the same direction, and a supporting frame therefor movably mounted in the machine frame, means carried by the supporting frame for shifting the magazines relatively thereto to bring one or another into operative position, with means for moving the supporting frame from its normal position to facilitate the removal of the magazines, the said means comprising a hand lever mounted in the machine frame and connections therefrom to the supporting frame.

4. In a typographical machine, the combination of a plurality of magazines, and a supporting frame therefor movably mounted in the machine frame, means carried by the supporting frame for shifting the magazines relatively thereto to bring one or another into operative position, with means for moving the supporting frame from its normal position to facilitate the removal of the magazines, the said means comprising the hand lever K, the shaft K¹ to which it is connected and mounted in the machine frame and provided with the arm K², and the link K³ pivoted to the arm K² and the supporting frame 50 respectively.

5. In a typographical machine, the combination of a plurality of magazines, and a supporting frame therefor movably mounted in the machine frame, means carried by the supporting frame for shifting the magazines relatively thereto to bring one or another into operative position, with means for moving the supporting frame from its normal position to facilitate the removal of the magazines, the said means comprising the hand lever K, the shaft K¹ to which it is connected and mounted in the machine frame and provided with the arm K², and the link K³ pivoted to the arm K² and the supporting frame 65 respectively, together with the stop K⁴ to

limit the movement of the hand lever K and hold the parts in their moved position.

6. In a typographical machine, the combination of assembling devices, a plurality of magazines, and means for shifting the magazines to bring one or another into operative relation to the assembling devices, with further means for lifting the magazines as a whole above the level of the assembling devices, the said means comprising a hand lever mounted in the machine frame and connections therefrom to the magazines, the parts being so proportioned that the throw of the handle will cause them to pass center, together with a stop to hold the hand lever in its operated position, for the purpose described.

7. In a typographical machine, the combination of two superposed magazines, and means for separating the magazines, the said means comprising a hand lever pivotally connected between its ends to one magazine and a link pivotally connected to one end of the lever and the other magazine respectively.

8. In a typographical machine, the combination of two superposed magazines, with means for separating the magazines, the said means comprising a hand lever pivotally connected to one magazine and connections therefrom to the other magazine, the said parts being so proportioned that the throw of the lever will cause them to pass center, together with a stop to hold the lever in its operated position.

9. In a typographical machine, the combination of two superposed magazines, and means for separating the magazines, the said means comprising the hand lever L pivotally connected between its ends to one magazine and provided with the projecting nose L⁵, and the link L³ pivotally connected to one end of the lever L and the other magazine respectively, and provided with a lug L⁶ to engage the nose L⁵ of the lever when the latter is in its operated position, for the purpose described.

10. In a typographical machine, the combination of two superposed magazines, and means for separating the magazines, said means comprising a hand lever and direct connections between it and the two magazines.

11. In a typographical machine, the combination of two magazines, a shift frame wherein they are mounted, the upper magazine being pivotally connected at its upper end to the shift frame, and means for swinging the upper magazine about its pivot away from the lower magazine, said means comprising a hand lever pivotally connected between its ends to the upper magazine, and a link pivotally connected to one end of the lever and the shift frame respectively.

12. In a typographical machine, the combination of two magazines, a shift frame whereon they are mounted, the upper magazine being pivotally connected at its upper end to the shift frame, and means for swinging the upper magazine about its pivot away from the lower magazine, said means comprising the hand lever L pivotally connected at L^1 to the upper magazine and provided with the nose L^5 , and the link L^8 pivotally connected at L^2 to the lower end of the lever L and at L^4 to the shift frame, the said link L^8 being provided with a stop lug L^6 to engage the nose L^5 of the handle L when the latter is in its operated position.

13. In a typographical machine, the combination of two magazines, and a shift frame wherein they are mounted, with means for separating the two magazines, the said means comprising a hand lever pivotally connected to the upper magazine and connections therefrom to the shift frame, the said parts being so proportioned that the throw of the lever will cause them to pass center, together with a stop to hold the lever in its operated position.

14. In a typographical machine, the combination of two superposed magazines, two supporting frames whereon they are mounted, and means for moving one of said supporting frames away from the other to separate the magazines, the said means comprising a hand lever pivoted to one frame, and direct connections from the hand lever to the other frame, substantially as shown and described.

15. In a typographical machine, the combination of a plurality of magazines, a supporting frame therefor movably mounted in the machine frame, means carried by the supporting frame and operable when said frame is in its normal position for shifting the magazines relatively thereto to bring one or another into operative position, and means for moving the supporting frame from its normal position to facilitate the removal of the magazines.

In testimony whereof, I have affixed my signature in presence of two witnesses.

DAVID S. KENNEDY.
